MACHINE FOR APPLYING PRESSURE TO
SOLES AND SHOES

Frank E. Stratton, Beverly, Mass., assignor to
United Shoe Machinery Corporation, Borough
of Flemington, N. J., a corporation of New
Jersey

Application July 24, 1940, Serial No. 347,174

89 Claims. (Cl. 12—37)

This invention relates to machines for use in applying pressure to shoe bottoms such, for example, as machines for cement attaching soles to shoes. The invention is illustrated, by way of example, as embodied in a turret type machine adapted for use in applying either sole laying or sole attaching pressure to shoe bottoms, the machine being provided with a plurality of work receiving units which consist of pads arranged for the reception of soles and shoes.

It is an object of this invention to provide an improved means for intermittently operating the conveyor, which in the illustrated machine consists of the rotatable turret, and controls for said means. As illustrated, the improved operating means consists of a multicylinder fluid motor which is arranged to move with the turret and intermittently to rotate the turret successively to bring the pads to a loading station. The operation of the fluid motor is regulated by a control device which is arranged to control the exhaust of pressure fluid from the different cylinders of the motor, and, as a further aspect of this feature of the invention, the control device is also arranged to admit pressure fluid to the cylinders in the exhaust position while the turret is at rest so as to equalize the pressure in all the cylinders at this time and render the motor inoperative.

It is a further object of this invention to provide an improved means for initiating the operation of the conveyor. To this end, the control device for the motor which operates the turret is coupled with the pad at the loading station by mechanism which urges the control device toward the motor operating position when a sole and shoe are pressed against the pad at the loading station. As illustrated, the control device comprises a shiftable member which is urged toward a motor operating position by a pressure-responsive member which is in turn coupled with a pressure-applying system associated with the pad at the loading station. In accordance with one embodiment of this feature of the invention, regulating means are provided for the pressure-responsive member and are arranged to prevent the operation of the pressure-responsive member until the pressure on the sole and shoe on the pad at the loading station reaches a predetermined level. In accordance with another embodiment of this feature of the invention, another type of regulating means is provided for the pressure-responsive member which is arranged to prevent the pressure acting on the pressure-responsive member from exceeding a predetermined level. The first embodiment mentioned above may be arranged automatically to start the motor when the pressure on a sole and shoe reaches a predetermined level, while the second embodiment may be arranged to urge the control device toward

the motor starting position with a force slightly less than that necessary to move it.

Another feature of the invention relates to the hydraulic system for operating the machine. As 5 illustrated, the hydraulic system consists of a high-pressure section which is arranged to apply pressure to the work on the pads, and a relatively low-pressure section which is arranged to operate the conveyor-moving means. The two sections 10 are continuously supplied with pressure fluid from a common source which is regulated by controls which are arranged to admit pressure fluid to the low-pressure system only when the pressure in the high-pressure system reaches a predetermined level.

In the illustrated machine, the work is pressed against the pads by means including a piston having a small section and a large section which are received respectively in a small chamber 20 which is connected to a source of pressure fluid, and a large chamber which is supplied with pressure fluid from the small chamber. Upon the release of the pressure acting on the piston, the pressure fluid in the large chamber normally escapes through an escape port in the large chamber which is uncovered at that time by a spring-operated valve. In accordance with another feature of this invention, further means are provided for permitting the escape of the pressure 25 fluid from the large chamber in the event that the spring-back valve fails to uncover the escape port when the pressure is reduced. As illustrated, this means consists of a passageway arranged to permit the escape of the pressure fluid from 30 the large chamber, and a valve located in that passageway and arranged to open in the event that the spring-operated valve fails to uncover the escape port.

Invention is also to be recognized in the means 40 for automatically disconnecting the operating lever from the fluid motor control valve during the rotation of the turret thereby to permit the valve to move independently of the operating lever and stop the movement of the turret at a predetermined time regardless of whether or not the operating lever has been returned to its inoperative position; in the arrangement of the fluid-operated means for controlling the sole and shoe locating gages and for biasing the shoe engaging 45 members towards an operative position after the sole and shoe have been properly located by the gages; in the guiding means for causing the pistons which apply pressure to the sole and shoe to move in a predetermined path; and in the control 50 means for regulating the operation of the valve which controls the flow of pressure fluid to the piston which forces the sole and shoe against the pad.

With the above and other objects in view, the 60 invention will now be described in connection

with the accompanying drawings and thereafter pointed out in the claims.

In the drawings,

Fig. 1 is a perspective view of a machine embodying this invention;

Fig. 2 is a vertical section through the machine taken on line II—II of Fig. 5, some of the parts being broken away to show details of the underlying structure;

Fig. 3 is a vertical section taken substantially along the line III—III of Fig. 2 looking in the direction of the arrows, the indexing control mechanism being omitted;

Fig. 4 is a view on an enlarged scale of a typical rotary valve used for controlling the indexing and gage operating systems;

Fig. 5 is a horizontal section through the machine taken on line V—V of Fig. 2 looking in the direction of the arrows;

Fig. 6 is a vertical section on an enlarged scale taken along the line VI—VI of Fig. 5 looking in the direction of the arrows;

Fig. 7 is an angular view on an enlarged scale of the indexing valve control mechanism shown in the lower right portion of Fig. 5;

Fig. 8 is a vertical section on an enlarged scale taken along line VIII—VIII of Fig. 5 looking in the direction of the arrows;

Fig. 9 is an elevation of the opposite end of the valve construction shown in Fig. 8;

Fig. 10 is a diagrammatic illustration of the hydraulic system embodied in the illustrated machine, the sections V—V, XII—XII and XIII—XIII being taken along similarly designated lines in Fig. 2 and showing the post turned 90° in a clockwise direction from its position in Fig. 5; while section XIV—XIV is taken along the line of that designation in Fig. 7, and sections XV—XV, XVI—XVI, XVII—XVII, and XVIII—XVIII are taken along lines of those designations in Fig. 5; and

Fig. 11 is a section taken along line XI—XI of Fig. 2 looking in the direction of the arrows.

Before describing the machine in detail a brief description will be given of its operation. The operator first places an unattached sole on the pad and then depresses the left treadle 170 which causes the sole locating mechanism accurately to position the sole on the pad. The operator next places a shoe on the sole, locating it with the aid of the gages and then moves a pair of balls 18 over the shoe and depresses the right treadle 268 which causes the balls to press the shoe into the pad. As the shoe is pressed into the pad the locating mechanism is automatically moved away from both the sole and the shoe. The operator now indexes the machine by depressing a hand lever 350 which causes the turret head to rotate through 90° and bring the next pad to the loading station. As the next pad moves toward the loading station the pressure fluid, which causes the balls to press the shoe into the pad, is automatically released and the balls are raised from the shoe so that the operator can remove it from the pad immediately after the pad reaches the loading station and repeat the loading operation described above.

The illustrated machine comprises a circular base 10 (Fig. 2) having an upstanding wall 12 which forms a supply tank or reservoir for the pressure fluid, preferably oil, used in the operation of the machine. Projecting from the central portion of the base is a raised platform 14 to which a post 16 is secured by bolts 18. The

platform is provided with openings 15 in its side walls so that the oil can circulate freely beneath the post. Mounted for rotation on the post is a turret consisting of a head 20 and a hollow depending column 22 which surrounds the post. The lower end of the column is supported by a roller bearing 24 (Fig. 2) mounted on a shoulder formed in the lower part of the post while the upper end of the column is positioned with respect to the post by a roller bearing 26 which is seated on a shoulder formed on the post adjacent to its upper end. The column 22 is made up of a lower part 28 which is constructed to function as a manifold and to control the operation of the machine in a manner which will hereinafter be described, and an upper portion 30 which depends from the head 20 and is fastened to the manifold by bolts 32.

The head 20 has formed therein four radially extending recesses 33 located 90° apart, which are normally covered by plates 60 (Fig. 1). Mounted in the recesses 33 are a like number of cylinders 34, 36, 38, 40 (Fig. 10) of a fluid-operated motor which rotates the turret successively to bring the pad boxes to the loading station which is in the front of the machine above the treadles. In the cylinders are pistons 42 (Fig. 2) which are connected by connecting rods 44, 46, 48 and 50 (Fig. 10) to a collar 52 which is rotatably mounted on a stationary pin 54. The pin 54 is located eccentrically of the center of the fixed post 16 and is mounted on a collar 56 which is fastened to the post by a key 58. The turret is rotated by successively exhausting two of the cylinders, allowing the other two cylinders to rotate the turret by pushing against the fixed pin 54. The mechanism for controlling the operation of the fluid motor will subsequently be fully described.

Mounted on the turret head between the cylinder receiving recesses are four pad boxes 64 (only one of which is shown in Fig. 1 for sake of clarity) which are successively brought to the loading station opposite the tray 62 (Fig. 1) by the rotation of the turret. The pad boxes are provided with pads 65 which are preferably of the type disclosed in Letters Patent of the United States No. 2,205,400, granted June 25, 1940, on an application filed in the name of Sidney J. Finn, while the shoe and sole locating mechanism is of the type disclosed in Letters Patent of the United States No. 2,262,759, granted November 18, 1941, on an application filed in the name of Sidney J. Finn.

The construction of the shoe pressing means associated with each pad is the same, so only a typical construction such as is shown in Figs. 2 and 3 will be described. When a shoe and a sole are properly located on the pad 65 at the loading station, the shoe is pressed into the pad by members 66, 68 (Figs. 1 and 3) which engage, respectively, the top of the cone of the last and the forepart of the shoe. The members are mounted on heightwise movable bails each consisting of a crosshead 70 and a pair of downwardly extending pivoted arms 72, 74 located on opposite sides of the pad. The bails are connected with each other by racks 76 which are fastened to the inner arms 72 and mesh with a pinion 78, so that movement of one of the bails is transmitted to the other and causes an equal and opposite movement of the other bail. The arms 74 on the side of the pad adjacent to the operator are more widely spaced than are the arms 72 so as to give the operator additional room in which to work when locating

a sole and a shoe on the pad. The upper ends of the bails are urged away from each other by springs 80 (Fig. 3) which are connected to the lower ends of the arms below their pivots.

When a shoe has been properly located on the pad, it is pushed against the pad by a piston 82 (Figs. 2 and 3) located in a cylinder 84 which is fastened to the turret head beneath the pad. The piston is connected to the lower ends of the bail arms 72, 74 by equalizing levers 86 which are fastened intermediate their ends to a shaft 88 and at their opposite ends rotatably receive rods 89 which are fastened to the bail arms. The shaft 88 is mounted in alined openings 89 formed in spaced ears 90 depending from a plate 92 which is bolted to a shoulder 94 that extends inwardly from the skirt portion of the piston 82. Located centrally of the plate 92 is a segment 96 having a downwardly facing wedge-shaped surface which lies between the sides of a complementally shaped groove formed on the periphery of a segment 98 keyed to the shaft 88. The alined openings 89 in the flanges 90 are larger in cross section than the shaft 88, and the shaft is normally held against the bottom surfaces of those openings by a pair of spring-backed plungers 100 (Fig. 2) slidably mounted in openings formed in the upper portions of the ears 90; the plungers acting on the equalizing levers 86 which are mounted on the ends of the shaft 88. While the shaft is held in the bottom of the openings 89, the members 96 and 98 are separated, as shown in Fig. 2, so that the shaft 88 can rock back and forth. Thus, when the bails are moved downwardly, the member 66 or 68 which first engages the shoe will rock the shaft 88 until the other member engages the shoe with an equal pressure. After this initial equalizing adjustment, the springs which back the plungers 100 yield, allowing the wedging surfaces on the members 96, 98 to contact each other and lock the bails to the piston during the period when substantial pressure is applied to the shoe.

The piston 82 is, broadly, of the quick-acting type disclosed in Letters Patent of the United States No. 2,231,963, granted February 18, 1941, on an application filed in the name of Frank E. Stratton. This piston has a head 102 (Fig. 3) located in a small chamber 104 and a lower shoulder 106 having a relatively large pressure receiving area located in a large chamber 108. It will be noted in passing that two separate pistons arranged in the manner disclosed in the above-mentioned Stratton patent can be used in the place of the single shouldered piston disclosed herein. The piston is forced downwardly in the cylinder by the delivery of pressure fluid through a pipe 105 to the relatively small chamber 104. The pressure fluid is supplied by a rotary pump 150 (Fig. 5) which draws the fluid from the reservoir through a strainer 152 and a pipe 154 and forces it through a pipe 156 to a rotary valve 158. From the valve the fluid is led through a pipe 160 to a riser pipe 162 (Fig. 2) in the stationary post 16, whence it passes through a port 164 to a chamber 166 (Fig. 10) in the upper part of the manifold and out through the pipe 105.

The chamber 104 is quickly filled, after which the pressure fluid rapidly forces the piston downwardly until the members 66, 68 engage the shoe. As the piston is moved downwardly, the displacement of its shoulder 106 causes fluid to be drawn up from the reservoir, through a pipe 110 in the post 16 (Fig. 2), a manifold opening 112, and a pipe 114 which opens onto a port 116 (Fig. 3) in a

passage 118 in the cylinder, whence the fluid passes into the chamber 108. The fluid drawn up in this manner does not apply pressure to the shoulder 106 but merely keeps the chamber 103 filled so that only a small amount of fluid need be added to build up pressure in this chamber.

When the members 66, 68 reach the shoe, the head portion 102 of the piston will have moved down far enough to uncover a passage 120, allowing the pressure fluid to flow from the small chamber 104 into the passage and to act on a sleeve valve 122 which is held by a backing spring 124 against a port that opens onto the large chamber 108. When the pressure builds up sufficiently to overcome the backing spring 124, the valve 122 is moved downwardly until it seals the port leading into the passageway 118, at which time openings 126 in the valve sleeve are uncovered in the chamber 108, allowing the pressure fluid to flow into the chamber 108 and build up pressure there which will act on the shoulder 106 of the large piston as well as on the small piston 102 and force the shoe into the pad.

After being loaded, the pad rotates with the turret head 12 until it again nears the loading station, when the pressure fluid acting on the piston 82 is released, at which time the piston is raised to move the bails away from the shoe by the action of a pair of heavy springs 128 (Fig. 2) which are connected respectively to the turret head and to the ends of a bar 130 mounted in the lower portion of the flanges 90. When the pressure in the chamber 108 is reduced the spring 124 raises the valve 122 and uncovers the passageway 118 allowing the fluid in the chamber 108 to escape rapidly down that passageway so that it will not retard the upward movement of the piston.

The extent to which the passage 120 is uncovered by the piston head 102 upon its downward movement depends upon the size and style of the shoe operated upon; for example, the piston moves further down to press a small flat shoe into the pad than it does to press a large shoe or one styled for a high heel. Thus, the passage 120 will be fully uncovered when a small shoe is operated upon, while it may be only slightly cracked when a very large shoe or one of an extremely high heeled style is operated upon. In the latter cases, it has been found that, occasionally, when the pressure fluid is released from the cylinder, the heavy springs 128 raise the piston so rapidly that the passage 120 is closed before the backing spring 124 can lift the valve 122 from its seat and permit the fluid in the chamber 108 to escape through the passage 118, with the result that the fluid in the chamber 108 is trapped there and prevents further upward movement of the bails. This difficulty is overcome by providing the piston 102 with a passage 137 (Fig. 3) which connects the chamber 108 to the chamber 104. The passage is sealed against the downward passage of fluid from the chamber 104 by a ball valve 138. Thus, in the event that pressure fluid is trapped in the chamber 108 after the pressure has been released from the chamber 104, the upward pressure of the trapped fluid on the ball 138 lifts it from its seat, allowing the pressure fluid in the chamber 108 to escape through the passage 137 until the pressure in the chamber 108 has been reduced sufficiently to permit the spring 124 to raise the

valve 122 and allow the remaining fluid to escape down the passage 118.

The piston is guided in its heightwise movement by a depending plate 132 (Fig. 2) having an elongated slot 134 in which slides one end of the bar 130. The guide plate 132 prevents rotation of the piston which would otherwise cause the bail arms 12, 14 to bind against the sides of the slots 136 in the turret head through which they move.

When the bails are in their inoperative positions (Fig. 3), that is, when they are moved away from each other so as to uncover the pad, the members 66, 68 overlie the gage mechanism, and if the piston were accidentally operated to its full extent at this time, the members would be forced downwardly against the gage mechanism and might cause considerable damage. To prevent this, the bail arms are provided with lugs 139 which lie above the surface of the turret head when the bails are in their up position (Fig. 1), and when the bails are in their inoperative position, lie slightly above shoulders 140 which surround the rear parts of the slots 136. If the pressure fluid is accidentally admitted to the chamber 104 when the bails are in this position, the lugs 139 will strike the shoulders 140 and will stop the downward movement of the piston before the small head 102 uncovers the passage 120. As the force exerted by the pressure fluid on the small head 102 is relatively small, the lugs will hold the piston in this position until the pressure fluid is released from the cylinder. Another advantage of this feature lies in the fact that it enables the operator to send one or more of the pads around the machine empty, as all that he need do to operate the machine in this manner is to make sure that the bails are in their inoperative positions, admit fluid to the chamber 104 so as to move the pins 139 into engagement with the shoulders 140, and then index the machine to bring the next pad to the loading station.

The forward portions of the slots 136, that is, the portions of the slots which underlie the lugs 139 when the bails are moved to a position where they overlie the shoe, are made enough wider than the openings in the rear portions of the slots which are surrounded by the shoulders 140 so that the lugs 139 can readily pass through the slots when the bails are moved downwardly to press a shoe against the pad.

When a sole is placed on the pad 64 at the loading station, it is positioned thereon by locating mechanism of the type described in the above-mentioned Finn Patent No. 2,262,759, which is operated by the treadle 170 through a control system which will now be described. The treadle is connected to a valve operating pawl 174 (Fig. 6) by a rod 172 which extends through an open ended pipe 175 threaded into an opening in the bottom of the reservoir and through an opening in the underlying treadle; the portion of the rod extending below the treadle having clamped thereon a collar 173 which normally engages the underside of the treadle. The upper end of the rod is located between a pair of spaced arms 178 that extend rearwardly from a sleeve 179 (Figs. 5 and 6) which is rotatably mounted on the stem 180 of the rotary plug in the valve 176, while the pawl 174 is located between the valve casing and the adjacent arm 178. The pawl 174 and the rod 172 are connected to the arms 178 by a pin 177. The arms are normally held in the raised

position shown in Fig. 6 by a spring 192 which urges an oppositely located forwardly extending arm 178 on the sleeve 179 downwardly against an adjustable stop screw 198 threaded into a flange 199 that projects inwardly from the wall 12.

The tooth 188 of the pawl 174 is normally seated in the uppermost of four equally spaced notches 181 in the periphery of a collar 182 which is keyed to the valve stem 180, the tooth being urged into the notch by a spring 194 which is connected at one end to the toothed portion of the pawl and at its other end to a pin 196 on the sleeve 179. The pawl tooth 188 has parallel front and rear surfaces which engage against the opposite sides of the notches in which it is seated and forms a positive two-way connection with the collar which enables the operator partly to open and to close the valve to adjust the sole locating mechanism while he is positioning a shoe on the pad.

When the treadle 170 is fully depressed the pawl 174 is rotated in a counterclockwise direction as viewed in Fig. 6 and moves the valve plug with it to its fully open position. Near the end of the downward movement of the treadle a tail 184 of the pawl strikes a pawl lifting stud 186, and as the treadle continues downwardly to the limit of its movement, the stud 186 causes the pawl tooth 188 to lift out of the notch in which it is seated until a beveled surface on the pawl tooth lies above the surface of the collar 182, at which time a spring-pressed plunger 190 located beneath the collar enters one of the notches 181 which moves opposite to it at this time and yieldingly resists further movement of the collar. When the treadle is released, a spring 192 connected to the arm 178 rotates the sleeve 179 in a clockwise direction, as viewed in Fig. 6, thereby causing the beveled surface on the pawl tooth 188 to ride up on the side of the notch until the pawl tooth rests on the periphery of the collar 182 and then to move with the collar until the tooth drops into the next notch; the pawl tooth being held against the periphery of the collar during its movement between notches by the spring 194.

The upward limit of movement of the treadle 170 is determined by engagement of a boss 200 on the upper side of the treadle with the under side of the base, while its lower limit of movement is determined by the engagement of a collar 202 on the rod 172 with a plate 204 seated on the upper end of the pipe 175, the treadle normally being held in its upper position by a spring 206.

When the valve 176 is moved to its inlet position by the treadle, it admits pressure fluid to a chamber 208 in a cylinder 209 (Figs. 3 and 10), where the fluid acts against the under side of a plunger 210, and raises the plunger against the resistance of a spring 212 until a sleeve 214 connected to the lower end of the plunger strikes against the lower end of the cylinder 209. The pressure fluid is supplied by the pump 150 and passes through the pipes 156 and 216 (Figs. 5 and 10) to a pressure control valve 218 whence it flows through a pipe 220 to a second pressure control valve 222 and then through pipes 224, 226, and 228 to the valve 176 and from there through a pipe 230 to the chamber 208. If desired, the pressure control valves 218 and 222 and also 444, which will be hereinafter referred to, may be similar to the pressure control valve 1070 described in the United States Letters Patent No. 2,047,185, issued July 14, 1936, on an application filed by Ballard et al.

When the plunger 210 is raised by the action

of the pressure fluid, it lifts a rod 232 (Fig. 3) which forms part of the operating linkage of the gaging mechanism associated with the pad box at the loading station and which overlies the plunger while the pad box is at that station. The upper end of the rod 232 is connected to a bell-crank lever 234 which is in turn connected to a bar 236 that corresponds to the bar 100 in the disclosure of the before-mentioned Finn Patent No. 2,262,759. Upward movement of the rod 232 rotates the lever 234 in a clockwise direction and moves the bar 236 to the right, as viewed in Fig. 6, causing the sole locating mechanism to position correctly a sole on the pad.

Clockwise movement of the bell-crank lever 234 also compresses a spring 238 sleeved about a rod 240 which is pinned to the upper end of the lever and passes through an opening in a plate 242 which is in turn connected with the arm 12 of the left bail by members 244, 246. The force exerted by the compressed spring 238 on the plate 242 is nearly strong enough to cause the bails to move toward each other so that the operator is materially assisted in moving them to a position above a shoe on the pad.

The locating mechanism is automatically released from the sole and the shoe after they have been pressed firmly into the pad. The release of the locating mechanism is effected by the depression of a plunger 250 in a chamber 249 which is connected to the chamber 108 by a passage 248, the plunger being forced downwardly when the pressure of the fluid in these chambers builds up sufficiently to overcome a backing spring 252 which surrounds the plunger. This, of course, takes place after the piston 82 has been forced down far enough to uncover the passageway 120 and the pressure has built up in the chamber 108. The downwardly moving plunger strikes the head 254 (Figs. 3 and 6) of the treadle rod 172 and moves the latter downwardly, causing the valve 176 to rotate to its next position, where the chamber 208 and the pipe 230 are connected to an exhaust pipe 231 which discharges into the reservoir (Figs. 6 and 10). The spring 212 which surrounds the plunger 210 will then move that member downwardly, allowing a spring 256 (Fig. 3) to rotate the lever 234 in a counterclockwise direction and move the locating mechanism to its inoperative position. As the lower end of the rod 172 is slideable in an opening in the treadle 170, downward movement of the rod caused by the action of the plunger 250 will not disturb the treadle.

There is a possibility that the lower ends of the plunger 250 and the rod 232 will be bent or broken when the turret is rotated to move a pad away from and back to the loading station due to the fact that the lower end of the plunger is pressed against the head 254 of the rod 172 when the pad moves away from the loading station, and when it moves back to the loading station the lower end of the rod 232 will strike against the head of the plunger 210 if the plunger has not fully returned to its down position. Accordingly, both the plunger 250 and the rod 232 have been made in two parts which are connected by a spring-closed hinged joint 258 which permits them to break when their lateral movement is resisted.

The rotary valve 158 which controls the flow of pressure fluid to the cylinder 84 is constructed to operate both as an inlet or supply valve and as an outlet or exhaust valve and is operated by two independent control systems. The first of these control systems, considered in the sequence of

their operation, is operated by the treadle 260 which is depressed when a sole and a shoe are properly located on the pad and moves the valve 158 to its inlet position where it admits pressure fluid to the cylinder 84 which causes the shoe to be pressed into the pad. The second control system moves the valve 158 to its exhaust position and is sequentially operated by each of four cams 264 (Fig. 5) which are mounted on the manifold

28 in predetermined relation to the four pads. The operation of the second system takes place as the different pads return to the loading station after having moved around the turret and effects the release of the pressure fluid from the cylinder associated with the returning pad so that the attached shoe and sole can readily be removed from the pad.

The first control system for operating the valve 158 consists of a pawl 266 (Figs. 5 and 8) having a tooth 268 which is successively seated in six equally spaced square notches 270 formed in a collar 272 which is keyed to the stem 274 of the plug in the valve 158. Rotatably mounted on the stem 274 (Fig. 8) is a sleeve 276 having two spaced rearwardly extending arms 278 which receive between them a treadle rod 280. The pawl 266 is located between the valve 158 and the adjacent arm 278, and both the treadle rod and the pawl are connected to the arms 278 by a transversely extending pin 282. The arms 278 are held in their up position shown in Fig. 8 by a spring 304 which is connected to a forwardly extending arm 284 on the sleeve 276 and holds that arm against an adjustable stop screw 286 mounted on the flange 199. The treadle rod 280 extends through an open ended pipe 290 (Fig. 8) to a point below the bottom of the reservoir (Fig. 2) where it is connected to the treadle 260 by a coupling similar to that disclosed in Fig. 7. The treadle is normally held against the under side of the reservoir by a spring 292, and its lower limit of movement is determined by the engagement between a collar 294 on the rod 280 and a plate 296 mounted on the top of the pipe 290.

When the treadle 260 is depressed the plug in the valve 158 is rotated by the pawl 266 and as the treadle nears its lower limit of movement the pawl tooth 268 is lifted out of the notch 270 in which it is seated by the engagement between its tail portion 298 and a stud 300. As the treadle reaches the end of its downward movement, a spring-backed plunger 302 seats itself in the lowermost notch 270 and holds the plug in its adjusted position until the next time it is rotated by the pawl. Upon release of the treadle the spring 292 raises the treadle and the spring 304, which is connected to the arm 284, rotates the sleeve 276 in a counterclockwise direction, as viewed in Fig. 8, until the arm engages the stop screw 286. As spring 306, which is connected to the pawl and to a pin 308 on the sleeve 276, causes the pawl tooth 268 to ride over the surface of the collar 272, as it moves with the sleeve until it drops into the next notch 270. It will be noted that the pawl tooth 268, like the pawl tooth 188, has parallel front and rear surfaces. These surfaces form a positive two-way connection with the collar 272 until the pawl is lifted out of the notch in which it is seated by the stud 300, thus making it possible for the operator to raise and lower the bails 10 as he adjusts a shoe on the pad.

When the loaded pad again approaches the loading station after having moved about the turret, the plug in the valve 158 is rotated, by

the second control system mentioned above, to its exhaust position where it permits the pressure fluid in the cylinder 84 to escape back to the reservoir and thus allow the springs 128 to raise the bails 78 to their up position. The second control system consists of a bell-crank lever 310 (Fig. 5) one arm of which is connected by a link 312 to an arm 288 (Fig. 2) which extends downwardly from the valve operating sleeve 276. The other arm of the bell-crank lever 310 is provided with a roller 314 (Fig. 5) which is located in the path of rotation of the cams 264 when the valve operating pawl 266 is in its upper position, shown in Fig. 8, so that the cam 264 associated with the pawl that is moving to the loading station will strike the roller 314 and cause the lever 310 to rotate in a clockwise direction, as viewed in Fig. 5, and move the plug in the valve 158 to its exhaust position.

A safety mechanism is applied to the valve 158 which permits an inlet passage of the valve to be opened and closed thereby to move the bails 78 up and down as the operator adjusts the shoe on the pad but which, once pressure has been fully applied to the pad, requires the operator fully to release the bails by moving the valve all the way to its exhaust position before pressure can again be applied to the shoe. This mechanism takes care of the situation which occasionally arises when an operator, after fully applying pressure to the shoe and taking his foot from the treadle 260, sees that the shoe is improperly adjusted and partly depresses the treadle a second time to raise the bails so that he can correct the adjustment of the shoe. It has been found that when the operator partly depresses the treadle the second time to raise the bails so that he can adjust the shoe he has a tendency to forget that the pawl 266 is positively connected to the collar 272 at this time and that the bails will again move downwardly when he lets the treadle rise, and he sometimes removes his foot from the treadle, thereby endangering his hand which has taken hold of the shoe.

The safety mechanism consists of a collar 318 (Figs. 5 and 9) pinned to a valve plug spindle 318 which projects from the left side of the valve 158, and a pawl 320 which co-operates with ratchet teeth 322 formed in spaced sections of the periphery of the collar 318. The ratcheted sections 322 correspond to the location of the slots 324 (Figs. 4 and 10) in the valve plug when positioned to exhaust the pressure fluid from the cylinder 84 and the smooth surfaces 326 on the collar 318 which extend between the ratcheted portions correspond to the inlet positions of the slots 324 when they connect the cylinder 84 with the pump 150. Thus, when the treadle 260 is depressed to move one of the slots 324 in the plug of the valve 158 to an inlet position, the tooth of the pawl 320 will ride over one of the smooth surfaces 326 so that the operator can raise and lower the treadle to control the bails while he is adjusting the shoe. However, once the treadle has been fully depressed and the slot moved all the way into its inlet position, the pawl tooth will drop into the first notch of the ratchet 322 so that the valve plug must be moved to its full exhaust position before the pawl tooth meets the next smooth surface 326, which permits the operator to again move the valve to its inlet position. The tooth of the pawl 320 is held against the surface of the collar 318 at all times by a spring 328 which is fastened at one end to the pawl and at its other end to the valve casing.

Each of the valves 158 and 176 (Fig. 5) is provided with a cylindrical plug of the type illustrated in Figs. 4 and 10. This plug has three equally spaced slots 324 which are successively moved to inlet and exhaust positions. As one of these slots is always in register with the pipe supplying pressure fluid, the registering slot will be filled with the pressure fluid which forces the plug against the opposite side of the valve casing, making the valve hard to turn. To overcome this resistance, each slot 324 is connected by passages 330 (Fig. 4) with oppositely located slots 332 on opposite sides of the slot 324. The slots 332 are sealed by the blank wall of the valve casing so that they form pockets for the pressure fluid, and being oppositely disposed to the slot 324 which is in register with the pipe supplying the pressure fluid, the action of the fluid in the slot 324 will be counteracted by the reaction of the pressure fluid in the pockets formed by the slots 332.

The turret is rotated by a fluid motor which is operated by pressure fluid from the pump 150 (Fig. 10) which flows from the pressure control valve 222, through the pipes 224, 334 to a riser pipe 336 in the stationary post 18, thence out through a port 338 and a recess 340 in the post to manifold chambers 342 which are connected to pipes 344 that lead to the cylinders of the fluid motor which are in propelling position. The chambers 342 in the manifold are separated by partitions 346 that slide over the surface of the post. The recess 340 in the post is sufficiently long so that it extends beyond the sides of the partition 346 which lies opposite to the port 338 and opens into the chambers 342 on both sides of that partition. The two chambers 342, which are connected to the cylinders in exhaust position, are connected by a recess 348 in the post to a riser pipe 348, thence to a pipe 352 which opens into a chamber 354 in a valve casing 356. Also opening into the chamber 354 is a pipe 358 which is connected through the pipes 226, 224 to the pressure control valve 222.

Operation of the fluid motor is controlled by a slide valve 368 (Fig. 2) which regulates the escape of the pressure fluid from the cylinders in the exhaust position and also functions as an index pin. The valve is mounted for reciprocation in the valve casing 356 from which it projects at both ends. The end 362 of the slide valve adjacent to the manifold 28 functions as the indexing pin and is provided with a roller 364 which is normally seated in one of four recesses 366 (Fig. 5) spaced 90 degrees apart in a cam 368 which is fastened to a shoulder 369 on the lower portion of the manifold by bolts 370 (Fig. 2). The bore in the valve casing 356 is of different diameters, the section adjacent to the manifold being of greater diameter than the section in the opposite end. The mid-portion of the bore contains two spaced circumferential grooves which open onto the pipes 352 and 358, and the bore between these grooves is of the same diameter as the larger section of the bore adjacent to the manifold. The slide valve 368 is constructed with a shoulder 372 of a diameter to make a sliding fit in the end of the valve casing adjacent to the manifold 28 and a smaller shoulder 374 of a diameter which is complementary to the smaller opening in the opposite end of the casing. As the shoulder 372 is larger in cross section than the shoulder 374, the pressure fluid in the mid-portion of the casing forces the slide valve to the right, as viewed in Figs. 2 and 10, and keeps the roller 364 in

engagement with the cam 368 while the turret is rotating and seated in the bottom of one of the recesses 366 while the turret is at rest. The portion of the slide valve between the shoulders 372 and 374 which is located between the grooves in the valve casing when the roller 364 is seated in the recess 366 is of reduced diameter so that the passage or chamber 354 connects the pipes 352 and 358 at this time.

Rotation of the turret is initiated by a hand lever 350 (Figs. 2 and 7) which withdraws the slide valve 360 part way from the recess 366 in which it is seated to a position where the roller 364 lies opposite to an inclined surface 376 (Fig. 5) on the indexing cam 368. When the slide valve reaches this position, the shoulder 372 will be displaced sufficiently to the left, as viewed in Fig. 10, to close the central part of the chamber 354, thus shutting off the pressure fluid from the cylinders 36, 38 which are in the exhaust position when the cylinders are located as shown in Fig. 10, and at the same time the shoulder 372 will have slightly uncovered the port 373 leading to the pipe 352 which allows the pressure fluid in the cylinders 36, 38 to escape through the pipe 352, past a reduced portion 378 of the slide valve 360, and then through a discharge pipe 380 into the reservoir. The escape of the pressure fluid from the cylinders 36, 38 permits the cylinders 34, 40 which are in the driving position to rotate the turret head and this rotation carries the inclined surface 376 of the cam 368 beneath the roller 364, forcing the slide valve 360 still further to the left, as viewed in Fig. 10, until the port 373 leading to the pipe 352 is fully uncovered. When the slide is in this position, the pressure fluid can escape most rapidly from the cylinders 36, 38 and the turret will rotate at its maximum speed.

As the pad to the left of the loading station approaches the loading station, an inwardly sloped surface 382 on the indexing cam 368 moves beneath the roller 364, and allows the slide 360 to move to the right, as viewed in Fig. 10, until the roller 364 reaches a relatively flat surface 384 on the indexing cam, when the slide valve will have moved to the right to a position where an opening 386 in the shoulder 372 is located in the groove opening onto the pipe 352 which allows the pressure fluid to escape from the exhausting cylinders. The opening 386 is connected through a small passageway 388 in the slide valve to a second opening 390 which at this time will be in register with a port 391 leading to an orifice plate 392 which opens onto a pipe 394 that discharges back into the reservoir. The restricted openings in the passageway 388 and the orifice plate 392 reduce the flow of fluid from the exhausting cylinders, thereby reducing the speed of rotation of the turret to a point where it is barely moving. This movement is stopped altogether when the roller 364 drops into the next recess 366 when the slide valve moves to the position shown in Fig. 10 where the shoulder 372 prevents further escape of fluid from the exhaust cylinders.

When the turret is at rest the roller 364 is seated in one of the recesses 366 and the slide valve shoulder 372 is in the position shown in Fig. 10 where the pipe 358 is connected to the pipe 352 by the chamber 354 so that the pressure fluid can flow through the chamber 354 to the cylinders 36, 38 in exhaust position. Thus, equal pressure is applied to all the pistons in the fluid motor at this time, thereby eliminating the rotational force which would otherwise be exerted

by the pistons in the driving position and tend to freeze the roller in the recess.

The hand lever 350 which operates the slide valve 360 is mounted in a socket 395 formed on a sleeve 396 (Figs. 2 and 7) which is pinned to one end of a shaft 397 mounted in a bearing 398 attached to a bracket 399 that is fastened to the top of a partition 400 which projects up from the base 10. The partition is located in the front portion of the base below the loading station, where it forms a support for the slide valve and elements of the slide valve operating mechanism. Pinned to the opposite end of the shaft 397 adjacent to the end of the bearing 398 opposite to the sleeve 396 is a crank arm 401, and rotatable on that end of the shaft is a forked arm 402 which is connected to the stem of the slide valve 360 by a pin 403 that is seated in the fork in the arm 402. The crank arm 401 is connected to the forked arm 402 by a latch 404 which hooks over a pin 406 that extends laterally from the arm 402. When the hand lever 350 is operated, the latch 404 causes the arm 402 to move with the crank arm 401 and to withdraw the slide valve 360 a sufficient distance from the cam 368 to remove it from the recess 366 and crack the port 373 (Fig. 10) leading to the exhaust cylinders, thereby initiating the rotating of the turret. As the turret rotates, the cam surface 376 moves the slide valve 360 further to the left, as viewed in Fig. 7, causing the forked arm 402 to move relatively to the crank arm 401 and the pin 406 to ride beneath a shoulder 408 on the latch and lift the same. When the latch is lifted sufficiently for its hooked end to clear the pin 406, a pivoted stop 410 mounted on the crank arm 401 is moved beneath a shoulder 414 on the latch 404 by a spring 412 and holds the latch in its raised position. Thus, the slide valve is free to move inwardly in response to the unbalanced pressure upon it away from the arm 401 as the contour of the cam 368 changes and stop the turret after a quarter of a revolution even if the hand lever 350 is held down by the operator. When the hand lever is allowed to return to its up position (Figs. 2 and 7), an abutment screw 416 strikes the lower end of the stop 410 and knocks it out from beneath the shoulder 414, allowing the spring 412 to pull the latch 404 down into engagement with the pin 406. Downward movement of the hand lever 350 is limited by a stop screw 420 mounted on a plate 422 which projects laterally from the sleeve 396 while return movement of the hand lever 350 (Fig. 7) is limited by a second abutment screw 418 which engages a shoulder 419 on the crank arm 401. The lever 350 is held in its up position by a spring 421 which is located between the base 10 and the plate 422 where it urges the sleeve 396 in a clockwise direction and holds the shoulder 419 against the screw 418.

Withdrawal of the slide valve 360 by the hand lever 350 is resisted by the force exerted by the pressure fluid on the slide valve shoulder 372 which tends to keep the end of the valve seated in one of the recesses 366. This resistance is largely overcome when the shoe is pressed into the pad by the action of a piston 424 (Fig. 10) which is mounted in a cylinder 426 (Fig. 7) that is screw fastened to the wall 12 above and in front of the sleeve 396. The piston 424 is connected by a link 428 to the rearwardly located end of a crank arm 430 which projects from the socket 395 so that pressure fluid acting on the piston 424 tends to pull the arm 430 forward and

depress the hand lever 350. Pressure fluid is conducted to the cylinder 426 (Fig. 10) by a pipe 432, a valve 434, and a pipe 436 which is connected to the pipe 160 that leads from the valve 158 to the pressure cylinder 84. Thus, as pressure builds up in the cylinder 84 and forces a shoe into the pad, it also builds up behind the piston 424 and tends to rotate the hand lever 350 in a counterclockwise direction, as viewed in Fig. 7, and move the slide valve away from the cam 368. The assistance rendered by the piston 424 is controlled by the adjustment of a backing spring 438 in the valve 434 which yields when the pressure builds up sufficiently to overcome the resistance of the spring and allows a plug 440 in the valve to move to the left and to close the port leading to the pipe 436, thereby preventing the passage of additional fluid through the valve. Movement of the valve 360 to the starting position can be made fully automatic by using a spring 438 of sufficient strength to prevent the movement of the plug 400 under pressures great enough to move the piston 424 to the left and cause the withdrawal of the valve from the recess 366 in which it is seated.

If desired, starting of the illustrated machine can be made fully automatic and be caused to take place only when a predetermined pressure has been applied to a shoe. This can be accomplished by by-passing the valve 434 with a pipe 442 and connecting into that pipe a pressure control valve 444 which can be set to open and permit the passage of pressure fluid to the cylinder 426 only when the pressure has been built up to a predetermined point. A two-way valve 446 may be provided so that the indexing mechanism can selectively be operated either by the manual control or under the automatic control just described.

The hydraulic apparatus in the illustrated machine includes a high-pressure system and a low-pressure system, both of which are supplied with pressure fluid by the pump 150. The high-pressure system is utilized to apply pressure to the shoe and to assist in the operation of the indexing mechanism, while the low-pressure system is used to operate the fluid motor and the sole locating mechanism. Pressure in the high-pressure system is usually between 150 pounds per square inch and 250 pounds per square inch, depending upon the work operated upon, and is regulated by the pressure control valve 218 (Fig. 10) which is adjusted by a manually operated control 219 (Figs. 1 and 5), the pressure being indicated by a conveniently located gage 448. Pressure fluid in the high-pressure system passes to the cylinder 84 of the pad at the loading station, through the pipe 156 (Fig. 10), the valve 158, and the pipes 160 and 165; and to the cylinders of the three pads away from the loading station, through a pipe 450 which branches off from the pipe 156 (Figs. 5 and 10), a check valve 452, and a riser pipe 454 located in the center of the stationary post 16, thence up to three passageways 456 which open on to chambers 166 in the manifold, whence the pressure fluid passes to the aforementioned cylinders.

The chambers 166 are separated by partitions 458 which control the flow of the pressure fluid to the cylinders in the following manner: After pressure has been applied to a shoe at the loading station by pressure fluid supplied through the riser pipe 162, the turret is rotated to move that shoe away from the loading station. During the initial part of this rotation the partition 458

immediately to the left of the port 164, as viewed in Fig. 5, moves past that port shutting off the riser pipe 162 from the cylinder 84, which is moving away from the loading station. As the riser pipe 162 is shut off, the partition 458 which forms the other end of the chamber 166 uncovers the adjacent passageway 456, which is connected to the riser pipe 454 that is also connected with the pump 150. The second and third passageways 456 are connected to the chamber 166 in a like manner during the two following indexing operations. Thus, the cylinder 84 is continuously connected with the pressure fluid supply as it moves from the loading station about the machine and to the station immediately to the left of the loading station. The check valve 452 in the line 450 leading to the riser pipe 454 shuts off automatically when the pressure drops in the line 156 while the cylinder 84 at the loading station is being filled and in this manner prevents fluctuations in the pressure applied to the shoes that are not at the loading station.

When the machine is operated a fourth time to move the shoe back to the loading station, the rear partition 458 moves past the left passageway 456 (Fig. 5) while the front partition uncovers the passageway 164. When the port 164 is closed by the front partition 458, the cam 254 strikes the lever 310 and moves the valve 158 to its exhaust position. This allows the pressure fluid in the cylinder 84 associated with the pad moving to the loading station to escape when the front partition uncovers the port 164, and the springs 128 to move the bails away from the shoe on that pad so that the shoe can readily be removed when it reaches the loading station.

When the pressure exceeds the setting of the pressure control valve 218 (Fig. 10), that valve opens and the pressure fluid passes through the pipe 220 to the second pressure control valve 222 which controls the pressure in the low-pressure system. The valve 222 is set to release under pressures in the neighborhood of 125 to 150 pounds per square inch, and when the pressure for which it is set is exceeded, the valve opens, allowing the pressure fluid to flow back to the reservoir. The valve 222 is controlled by a hand wheel 464 (Fig. 5) and the pressure in the low-pressure system is indicated on a gage 466. From the pipe 220 the pressure fluid flows through pipes 334 and 358 to the cylinders of the fluid motor and controls the turret in a manner which has already been described.

Mounted on the rear of the base 10 (Fig. 1) is an electric motor 468 which drives the pump 150 through a pulley 470 fastened to the motor shaft 471, a belt 472, and a pulley 474 connected to the pump shaft 475. The motor is controlled by a push button switch 476 fastened to the machine frame adjacent to the loading station in a location convenient to the operator. The sides of the machine are closed by swinging plates 478 pivoted on vertical posts 480 which are mounted on lugs 482 that jut out from the base wall 12.

Having described the construction of the illustrated machine, its operation will now be explained with particular reference to Figs. 2, 3 and 10. The operator first places a sole on the pad 165 at the loading station and then depresses the treadle 170 which moves the valve 176 to its inlet position where it admits pressure fluid to the cylinder 209. This causes the plunger 210 to operate the sole locating mechanism and cause the latter correctly to position the sole on the pad.

He then places a shoe upon the sole and locates the same with respect to the sole with the aid of gages provided for that purpose, after which he moves the bails 70 above the shoe. The treadle 260 is then depressed to move the valve 158 to the inlet position where it admits pressure fluid to the cylinder 84 underlying the pad at the loading station, which causes the bails 70 to press the shoe into the pad. When the pressure in the cylinder 84 has built up to a predetermined point, it depresses the plunger 250 which strikes the valve 176 and moves it to its exhaust position, allowing the pressure fluid that had lifted the plunger 210 to escape. This permits the spring 212 to move the plunger 210 downwardly and the spring 256 to withdraw the locating mechanism from the shoe and sole.

Having applied pressure to the shoe on the pad at the loading station, the operator depresses the hand lever 350, partly withdrawing the slide valve 388 from the notch 366 in the indexing cam 368 and initiates rotation of the turret. As the turret rotates, the slide valve is first forced back by the cam 368, increasing the speed of rotation of the turret, and is then allowed to move inwardly again as the notch 366 associated with the pad moving to the loading station approaches the indexing pin, thereby slowing down the movement of the turret until the indexing pin drops into the notch, when the movement is completely stopped. In the early part of the movement of the turret, the chamber 166 associated with the cylinder 84 beneath the pad moving toward the loading station uncovers the port 164, at which time the cam 264 (Fig. 5) associated with that pad strikes the roller 314 on the bell-crank lever 310 and moves the valve 158 to its exhaust position. This allows the pressure fluid in the cylinder 84 to escape back to the reservoir and the heavy springs 128 to lift the bails from the shoe so that the operator can take the shoe from the pad without delay when it arrives at the loading station.

Having thus described my invention, what I claim as new and desire to secure by Letters Patent of the United States is:

1. In a shoe machine, a conveyor, a plurality of work receiving units on said conveyor, and a multicylinder fluid motor arranged to operate said conveyor and directly connected thereto.

2. In a shoe machine, a conveyor, a plurality of work receiving units on said conveyor, and a multicylinder fluid motor movable with said conveyor and arranged to operate the conveyor step by step.

3. In a shoe machine, a conveyor, a plurality of work receiving units on said conveyor, a fixed abutment associated with the conveyor, and a fluid motor movable with the conveyor and so connected to the abutment that the conveyor is operated by the reaction of the fluid motor against the abutment.

4. In a shoe machine, a conveyor, a plurality of work receiving units on said conveyor, an abutment associated with the conveyor, a multicylinder fluid motor mounted on the conveyor and connected with the abutment, and means for rendering the cylinders sequentially effective to react against the abutment and thereby to operate the conveyor.

5. In a machine for operating upon shoes, a turret mounted for rotation and a multicylinder fluid motor arranged to rotate the turret and directly connected thereto.

6. In a machine for operating upon shoes, a 75

turret mounted for rotation, a fluid motor for rotating the turret, and a manifold mounted for movement with the turret and arranged to control the operation of the fluid motor.

5 7. In a machine for operating upon shoes, a stationary post, a turret rotatably mounted on the post, an abutment on the post located eccentrically to the axis of the post and a fluid motor mounted on the turret and arranged to react against the abutment to cause the rotation of the turret.

8. In a machine for operating upon shoes, a stationary post having fluid conducting passages, a turret having a sleeve rotatable on the post, a 15 portion of said sleeve comprising a manifold and having chambers opening onto the passages in the post, a fluid motor for rotating the turret step by step, and means for connecting the manifold to the fluid motor.

20 9. In a machine for operating upon shoes, a stationary post having fluid conducting passages, a turret including a sleeve rotatably mounted on the post, a portion of said sleeve comprising a manifold having chambers opening onto the 25 passages in the post, a fluid motor mounted on the turret and arranged to rotate the turret, and means for connecting the manifold with the fluid motor.

10. In a machine for operating on shoes, a 30 turret mounted for rotation, a fluid motor for rotating the turret, said fluid motor being arranged for movement with the turret, means for controlling the fluid motor, an indexing pin operatively associated with said means, and a cam 35 connected with the turret for movement therewith, said cam having notches for the reception of the indexing pin when the turret reaches a predetermined position.

11. In a machine for operating upon shoes, a 40 rotatable turret having a plurality of work receiving units, a fluid motor for moving the turret step by step successively to bring the units to a loading station, a valve for controlling the fluid motor, an indexing pin operatively associated 45 with the valve, and a cam connected with the turret, said cam having notches located in predetermined relation to said units for the reception of the indexing pin when the units reach the loading station.

12. In a shoe machine, a conveyor, a plurality 50 of work receiving units on said conveyor, a fluid motor for operating the conveyor, and means for regulating the exhaust of the pressure medium from the fluid motor to control its operation.

13. In a shoe machine, a conveyor, a plurality 55 of work receiving units on said conveyor, a multi-cylinder fluid motor for operating the conveyor, and means for selectively regulating the exhaust of the pressure medium from the cylinders to control the operation of the motor.

14. In a shoe machine, a conveyor, a plurality 60 of work receiving units on said conveyor, a multi-cylinder fluid motor for moving said conveyor step by step successively to move the units to a loading station, a pressure line, a manifold arranged successively to connect the cylinders to the pressure line, an exhaust line connected with said manifold, the manifold being arranged to connect the exhaust line to the cylinder opposite to the one connected to the pressure line, and a valve for controlling the exhaust of the pressure fluid from the cylinder connected to the exhaust line.

15. In a shoe machine, a conveyor, a plurality 70 of work receiving units on said conveyor, a multi-cylinder fluid motor for moving said conveyor step by step successively to move the units to a loading station, a pressure line, a manifold arranged successively to connect the cylinders to the pressure line, an exhaust line connected with said manifold, the manifold being arranged to connect the exhaust line to the cylinder opposite to the one connected to the pressure line, and a valve for controlling the exhaust of the pressure fluid from the cylinder connected to the exhaust line.

cylinder fluid motor for operating said conveyor step by step successively to move the units to a loading station, and means for applying equal pressure to all of the cylinders when the conveyor is at rest.

16. In a shoe machine, a conveyor, a plurality of work receiving units on said conveyor, a multi-cylinder fluid motor for moving said conveyor step by step successively to bring the units to a loading station, a manifold associated with the cylinders, a pressure line and an exhaust line connected with said manifold for selective connection with the cylinders of the motor, and a valve connected to the exhaust line and to the pressure line, said valve being arranged to control the speed of the motor by regulating the exhaust of the pressure fluid from the cylinder in exhaust position and when the machine is at rest to admit pressure fluid to the cylinder in exhaust position, thereby to equalize the pressure in all cylinders.

17. In a shoe machine, a conveyor, a plurality of work receiving units on the conveyor, fluid operated means for moving said conveyor step by step successively to bring the units to a loading station, a valve for controlling the operation of the fluid operated means, and a cam associated with said conveyor and arranged to regulate the position of the valve.

18. In a shoe machine, a conveyor, a plurality of work receiving units on the conveyor, a fluid motor for moving the conveyor step by step successively to bring the units to a loading station, a fluid system for supplying pressure fluid to the motor, a valve for controlling the flow of pressure fluid in said system, and a cam associated with the conveyor and arranged to regulate the position of the valve.

19. In a shoe machine, a conveyor, a plurality of work receiving units on said conveyor, fluid operated means mounted on the conveyor and arranged to move the conveyor step by step successively to bring the units to a loading station, a valve for controlling the operation of the fluid operated means, and a cam movable with the conveyor and arranged to regulate the position of the valve during the operation of the conveyor.

20. In a shoe machine, a conveyor, a plurality of work receiving units on said conveyor, fluid operated means for moving the conveyor step by step successively to bring the units to a loading station, a valve for regulating the fluid operated means during the operation of the conveyor, a cam operatively connected with the conveyor and arranged for sliding engagement with the valve, and means for holding the valve in engagement with the cam.

21. In a shoe machine, a conveyor, a plurality of work receiving units on said conveyor, fluid operated means for moving said conveyor step by step successively to bring the units to a loading station, a cam movable with said conveyor and having notches arranged successively to reach a predetermined position when the units reach the loading station, a valve for controlling the fluid operated means, said valve being arranged to seat in the notch in the predetermined position when the conveyor is at rest and to function as an indexing pin.

22. In a shoe machine, a conveyor, a plurality of work receiving units on said conveyor, a notched cam movable with the conveyor, fluid operated means for moving said conveyor step by step successively to bring the units to a load-

ing station, a valve for controlling the fluid operated means, said valve being arranged to seat successively in the notches in the cam between the movements of the conveyor, and means for partly withdrawing the valve from the notch in which it is seated to initiate the operation of the conveyor, said cam having surfaces arranged to increase the opening of the valve after the movement of the conveyor has been initiated to increase the speed of the conveyor movement.

23. In a shoe machine, a conveyor, a plurality of work receiving units on said conveyor, fluid operated means for moving the conveyor step by step successively to bring the units to a loading station, a valve for controlling the fluid operated means, a cam having spaced notches in which the valve successively seats between the operations of the conveyor, said cam having surfaces arranged to regulate the position of the valve during the operation of the conveyor and nearly to close the valve near the end of each operation, the valve being arranged at this time to restrict the flow of the pressure fluid from the fluid operated means and thereby to reduce the speed of the conveyor.

24. In a shoe machine, a conveyor, a plurality of work receiving units on said conveyor, fluid operated means for moving the conveyor step by step successively to bring the units to a loading station, a valve for controlling the fluid operated means, a cam arranged for cooperative engagement with the valve, the cam having spaced notches arranged to receive a portion of the valve while the conveyor is at rest and surfaces arranged to regulate the operation of the valve during the movement of the conveyor, said surfaces being arranged to fully open the valve during the early part of each operation of the conveyor thereby to move the conveyor at a maximum speed and then to allow the valve nearly to close as the next notch approaches thereby to slow down the speed of the conveyor.

25. In a shoe machine, a conveyor, a plurality of work receiving units on the conveyor, fluid operated means for moving the conveyor step by step successively to bring the units to a loading station, a fluid system for supplying pressure fluid to the fluid operated means, a valve for controlling the flow of pressure fluid in said system, said valve being adapted to register with a restricted orifice when moved to a predetermined position and reduce the flow of the pressure fluid, and a cam associated with the conveyor and arranged to control the valve during the movement of the conveyor and to locate the valve at the predetermined position near the end of the movement of the conveyor thereby to reduce the speed of the conveyor.

26. In a machine for operating on shoes, the combination of a rotatable turret, a fluid motor for operating said turret step by step, a valve for controlling the operation of the fluid motor, and a cam mounted on the turret in cooperative relation with the valve, the cam having a plurality of spaced notches for the reception of a portion of the valve when the turret is at rest and valve operating surfaces between the notches, each of the surfaces comprising an abruptly sloped portion on the advancing side of the notch arranged to open the valve wide at the beginning of the rotation of the turret to cause the turret to move at a maximum speed, a portion of uniform radius extending from the abruptly sloped portion to the vicinity of the next notch in the advancing direction of the cam, and a por-

tion of diminishing radius adjacent to the next notch.

27. In a shoe machine, a conveyor, a plurality of work receiving units on the conveyor, a fluid motor for moving said conveyor step by step successively to bring the units to a loading station, a valve arranged to control the exhaust of pressure fluid from said motor, and a cam associated with said conveyor for regulating the position of the valve.

28. In a shoe machine, a conveyor, a plurality of work receiving units on the conveyor, a multi-cylinder fluid motor movable with the conveyor and arranged to move the conveyor step by step successively to bring the units to a loading station, a valve for regulating the exhaust of the pressure medium from the fluid motor to control its operation, and a cam movable with the conveyor and arranged to control the position of the valve during the operation of the conveyor.

29. In a machine for applying pressure to shoe bottoms, a rotatable turret, a plurality of pressure applying units on said turret, a fluid motor for rotating the turret to bring the units successively to a loading station, a notched cam movable with the turret, a combined valve and indexing pin associated with said cam, said combined valve and indexing pin being arranged to render the fluid motor inoperative when seated in a notched portion of the cam and to control the operation of the motor when in engagement with a surface of the cam between successive notches.

30. In a machine for applying pressure to shoe bottoms, a conveyor, a plurality of pressure applying units on said conveyor, means for operating the conveyor to bring the units successively to a loading station, a displaceable device for controlling the operation of the conveyor operating means, a cam associated with the conveyor for controlling the position of the device during the operation of the conveyor, said cam having notches arranged for the reception of a portion of the device when the conveyor is at rest, means for applying pressure to the unit at the loading station, and means responsive to the pressure in said unit arranged partly to withdraw the device from the notch in which it is seated when the pressure in the unit at the loading station reaches a predetermined level, thereby to initiate movement of the conveyor.

31. In a machine for applying pressure to shoe bottoms, a rotatable turret, a plurality of fluid operated pressure applying units on said turret, a fluid motor for operating the conveyor to bring the units successively to a loading station, a valve for controlling the operation of a fluid motor, a cam mounted on said turret and arranged to control the position of the valve during the movement of the turret, said cam having notches located in a predetermined relation to the units and arranged for the reception of a portion of the valve when the turret is stationary, a piston connected with said valve, means for applying fluid pressure to the unit at the loading station, said last named means being arranged to subject the piston to the action of the pressure fluid in said unit thereby to urge the piston in a direction to withdraw the valve from the notch on which it is seated.

32. In a shoe machine, a conveyor, a plurality of work receiving units on said conveyor, a fluid motor for moving the conveyor step by step successively to bring the units to a loading station, a valve for controlling the operation of the fluid

motor, a cam associated with the valve and having spaced notches arranged successively to receive the valve when the conveyor is at rest, the valve being arranged to stop the operation of the fluid motor when seated in the notches, means for urging the valve toward the cam, and means for assisting the operator in moving the valve from the notch in which it is seated to initiate the next operation of the fluid motor.

10 33. In a shoe machine, a conveyor, a plurality of work receiving units on said conveyor, a fluid motor for moving the conveyor step by step successively to bring the units to a loading station, a valve for controlling the operation of the fluid motor, an indexing pin connected with said valve, a cam associated with the conveyor and having notches arranged successively to receive the indexing pin when the conveyor is at rest, said valve being constructed and arranged to stop the motor when the indexing pin is seated in the notches, and means associated with the work receiving unit at the loading station and arranged automatically to withdraw the indexing pin from the notch in which it is seated when the work is fixed to the work receiving unit.

20 34. In a machine for operating on shoes, a turret mounted for rotation, said turret having a plurality of work receiving units, a motor for rotating said turret step by step successively to bring the units to a loading station, a shiftable member for controlling the operation of the motor, and means for urging the shiftable member toward a position where it initiates the operation of the motor, said means being associated with the instrumentalities of the work receiving unit at the loading station and effective when a work piece is fixed to that unit.

30 35. In a machine for operating on shoes, a turret mounted for rotation, said turret having a plurality of work receiving units, a fluid motor for rotating the turret step by step successively to bring the units to a loading station, an indexing pin, a notched member mounted on the turret and arranged for engagement by the indexing pin while the turret is at rest, means for urging the valve toward the notched member, and fluid operated means arranged to assist the operator to withdraw the indexing pin from a notch in said member to initiate the operation of the turret, said fluid operated means comprising a cylinder connected to the pressure fluid source, a piston in the cylinder and connections between the piston and indexing pin.

40 36. In a machine for applying pressure to shoe bottoms, a conveyor, a plurality of pressure applying units carried by the conveyor, means for operating the conveyor step by step successively to bring each unit to a loading station, means for applying pressure to the pressure applying unit at the loading station, and means operative when the pressure on the pressure applying unit at the loading station reaches a predetermined level for initiating the operation of the conveyor operating means.

45 37. In a machine for applying pressure to shoe bottoms, a conveyor, a plurality of pressure applying units carried by the conveyor, means for operating the conveyor step by step successively to bring each unit to a loading station, and fluid means responsive to the pressure in the pressure applying unit at the loading station for initiating the operation of the conveyor operating means when the pressure in the unit at the loading station reaches a predetermined level.

50 38. In a machine for applying pressure to shoe

bottoms, a conveyor, a plurality of fluid operated pressure applying units carried by the conveyor, means for operating the conveyor step by step successively to bring each unit to a loading station, fluid operated means for applying pressure to the pressure applying unit at the loading station, and means operative when the pressure on the fluid operated pressure applying unit at the loading station reaches a predetermined level for initiating the operation of the conveyor operating means.

39. In a machine for applying pressure to shoe bottoms, a conveyor, a plurality of pressure applying units carried by the conveyor, fluid operated means for moving the conveyor step by step successively to bring each unit to a loading station, means for applying pressure to the pressure applying unit at the loading station, and means operative when the pressure in the pressure applying unit at the loading station reaches a predetermined level for initiating the operation of the fluid operated means.

40. In a machine for applying pressure to shoe bottoms, a conveyor, a plurality of fluid operated pressure applying units carried by the conveyor, fluid operated means for moving the conveyor step by step successively to bring each unit to a loading station, fluid pressure means for applying pressure to the pressure applying unit at the loading station, and means controlled by the fluid pressure in the pressure applying unit at the loading station for initiating the operation of the fluid operated conveyor moving means when the pressure in the unit at the loading station reaches a predetermined level.

41. In a machine for applying pressure to shoe bottoms, a conveyor, a plurality of pressure applying units carried by the conveyor, a motor for moving the conveyor step by step successively to bring each unit to a loading station, means for initiating the operation of the motor, means for applying pressure to the pressure applying unit at the loading station, and means responsive to the pressure in the pressure applying unit at the loading station for actuating the motor initiating means.

42. In a machine for applying pressure to shoe bottoms, a conveyor, a plurality of pressure applying units carried by the conveyor, a motor for moving the conveyor step by step successively to bring each unit to a loading station, means for applying pressure to the pressure applying unit at the loading station, a displaceable member for initiating the operation of the motor, and means controlled by the pressure in the unit at the loading station for displacing said member.

43. In a machine for applying pressure to shoe bottoms, a conveyor, a plurality of pressure applying units carried by the conveyor, a motor for moving the conveyor step by step successively to bring each unit to a loading station, fluid means for applying pressure to the pressure applying unit at the loading station, a displaceable member for initiating the operation of the motor, a cylinder having a piston operatively connected with the displaceable member, and means for connecting the cylinder with said fluid means so that the pressure fluid acting on the piston urges the displaceable member toward its motor operating position.

44. In a machine for applying pressure to shoe bottoms, a conveyor, a plurality of pressure applying units carried by the conveyor, a fluid motor for operating the conveyor step by step successively to bring each unit to a loading sta-

tion, means for applying pressure to the pressure applying unit at the loading station, a valve for initiating the operation of the fluid motor, and means responsive to the pressure in the unit at the loading station for moving the valve to its motor operating position.

45. In a machine for applying pressure to shoe bottoms, a conveyor, a plurality of pressure applying units carried by the conveyor, a fluid motor for operating the conveyor step by step successively to bring each unit to a loading station, fluid means for applying pressure to the pressure applying unit at the loading station, a valve for initiating the operation of the fluid motor, and a piston controlled by the fluid means acting on the unit at the loading station for moving said valve to its motor operating position when the pressure in the unit reaches a predetermined level.

46. In a machine for applying pressure to shoe bottoms, a conveyor, a plurality of fluid operated pressure applying units carried by the conveyor, means for operating the conveyor step by step successively to bring each of the units to a loading station, a control for said conveyor operating means, a displaceable member for operating the control, means for conducting pressure fluid to the unit at the loading station, and means connected with the pressure fluid conducting means for subjecting the displaceable member to the action of the pressure fluid, said last named means including a valve arranged to allow the passage of pressure fluid to the displaceable member only when the pressure in the unit at the loading station reaches a predetermined level.

47. In a machine for applying pressure to shoe bottoms, a conveyor, a plurality of fluid operated pressure applying units carried by the conveyor, means for operating the conveyor step by step successively to bring each unit to a loading station, a control for said conveyor operating means, a cylinder having a piston connected with said control, means for conducting pressure fluid to the unit at the loading station, a conduit for connecting the pressure fluid conducting means with the cylinder, and a pressure control valve in said conduit arranged to prevent the flow of pressure fluid to the cylinder until the pressure in the unit at the loading station reaches a predetermined level.

48. In a machine for applying pressure to shoe bottoms, a conveyor, a plurality of fluid operated pressure applying units carried by the conveyor, a fluid motor for operating the conveyor step by step successively to bring each unit to a loading station, a valve for controlling the operation of the fluid motor, a conduit for conducting pressure fluid to the unit at the loading station, a piston for operating the motor controlling valve, said piston being arranged for operation by the pressure fluid acting on the unit at the loading station, and a pressure control valve for controlling the application of pressure to said piston.

49. In a machine for applying pressure to shoe bottoms, a rotatable turret, a plurality of fluid operated pressure applying units carried by said turret, a multicylinder fluid motor arranged to rotate said turret, a valve for controlling the operation of the fluid motor by controlling the exhaust from selected cylinders, a piston operatively connected with said valve, a conduit connecting the unit at the loading station with a fluid pressure source, and means for subjecting

the piston to the action of the pressure fluid in the conduit, said means including a pressure control valve arranged to open and permit the passage of pressure fluid to the piston only after pressure in the unit at the loading station reaches a predetermined level.

50. In a machine for applying pressure to shoe bottoms, a conveyor, a plurality of fluid operated pressure applying units carried by the conveyor, means for operating the conveyor step by step successively to bring each unit to a loading station, a control for said conveyor operating means, a displaceable member for operating the control, means for conducting pressure fluid to the unit at the loading station, and means connected with the pressure fluid conducting means for subjecting the displaceable member to the action of the pressure fluid, said last-named means including a valve having a spring biased member arranged to shut off the flow of pressure fluid toward the displaceable member when the pressure in the unit at the loading station reaches a predetermined level.

51. In a machine for applying pressure to shoe bottoms, a conveyor, a plurality of fluid operated pressure applying units carried by the conveyor, means for operating the conveyor step by step successively to bring each unit to a loading station, a control for said conveyor operating means, a cylinder having a piston connected with said control, means for conducting pressure fluid to the unit at the loading station, a conduit for connecting the pressure fluid conducting means with the cylinder, and a valve in said conduit having a spring biased member arranged to close the valve when the pressure in the unit at the loading station reaches a predetermined level.

52. In a machine for applying pressure to shoe bottoms, a conveyor, a plurality of pressure applying units carried by said conveyor, means for moving the conveyor to bring the units successively to a loading station, a hydraulic system for applying pressure to the unit at the loading station, and a second hydraulic system for operating the conveyor moving means, the second hydraulic system being arranged to operate at a different pressure level than the first-mentioned hydraulic system.

53. In a machine for applying pressure to shoe bottoms, a conveyor, a plurality of pressure applying units carried by said conveyor, means for moving the conveyor to bring the units successively to a loading station, a high pressure hydraulic system for applying pressure to the unit at the loading station, and a relatively low pressure hydraulic system for operating the conveyor moving means.

54. In a machine for applying pressure to shoe bottoms, a conveyor, a plurality of pressure applying units carried by said conveyor, means for moving the conveyor to bring the units successively to a loading station, a hydraulic system for applying pressure to the unit at the loading station, a second hydraulic system for operating the conveyor moving means, said second hydraulic system being arranged to operate at a different pressure level than the first-mentioned hydraulic system, and a valve arranged to admit pressure fluid to the lower pressure hydraulic system only when the pressure in the higher pressure hydraulic system reaches a predetermined level.

55. In a machine for applying pressure to shoe bottoms, a conveyor, a plurality of pressure applying units carried by said conveyor, means for

5 moving the conveyor to bring the units successively to a loading station, a high pressure hydraulic system for applying pressure to the unit at the loading station, a relatively low pressure hydraulic system for operating the conveyor moving means, and a pressure control valve arranged to admit pressure fluid to the low pressure hydraulic system only when the pressure in the high pressure system exceeds a predetermined level.

10 56. In a machine for applying pressure to shoe bottoms, a conveyor, a plurality of pressure applying units carried by said conveyor, means for moving the conveyor to bring the units successively to a loading station, a high pressure hydraulic system for applying pressure to the unit at the loading station, a relatively low pressure hydraulic system for operating the conveyor moving means, a pressure control valve for admitting pressure fluid to the low pressure hydraulic system from the high pressure system only when the pressure in the high pressure system reaches a predetermined level, and a valve connected into the low pressure hydraulic system and arranged to permit the escape of pressure fluid from the low pressure hydraulic system when the pressure exceeds a predetermined level in that system.

15 57. In a machine for applying pressure to shoe bottoms, a conveyor, a plurality of pressure applying units carried by said conveyor, means for moving the conveyor to bring the units successively to a loading station, a hydraulic system for applying pressure to the unit at the loading station, a second hydraulic system for operating the conveyor moving means, the second hydraulic system being arranged to operate at a different pressure level than the first-mentioned hydraulic system, a valve in the second hydraulic system for controlling the operation of the conveyor moving means, and means responsive to the pressure in the first hydraulic system for urging said valve toward a position where it initiates the movement of the conveyor.

20 58. In a machine for applying pressure to shoe bottoms, a conveyor, a plurality of pressure applying units carried by said conveyor, means for moving the conveyor to bring the units successively to a loading station, a hydraulic system for applying pressure to the unit at the loading station, a second hydraulic system for operating the conveyor moving means, the second hydraulic system being arranged to operate at a lower pressure level than the first-mentioned hydraulic system, a valve in the second hydraulic system for controlling the movement of the conveyor, and pressure responsive means associated with the first-mentioned hydraulic system for urging the valve to a position where it initiates the movement of the conveyor.

25 59. In a machine for applying pressure to shoe bottoms, a conveyor, a plurality of pressure applying units carried by said conveyor, means for moving the conveyor to bring the units successively to a loading station, a high pressure hydraulic system for applying pressure to the unit at the loading station, a relatively low pressure hydraulic system for operating the conveyor moving means, a valve in the low pressure system for controlling the movement of the conveyor, a cylinder having a piston operatively connected with said valve, said cylinder being connected with the high pressure system so that the pressure in the high pressure system urges the piston in a direction to move the valve to a posi-

tion where it initiates the movement of the conveyor.

60. In a shoe machine, a conveyor, a plurality of work receiving units carried by the conveyor, means for moving the conveyor to bring the units successively to a loading station, a controller for said conveyor moving means, means for urging the controller toward an inoperative position, means arranged to move the controller from the inoperative position to an operative position where it initiates the movement of the conveyor, and means for automatically disconnecting the controller moving means from the controller after the movement of the conveyor has been initiated thereby to allow the controller to stop the movement of the conveyor independently of the subsequent movement of the controller moving means.

61. In a shoe machine, a conveyor, a plurality of work receiving units carried by the conveyor, means for moving the conveyor to bring the units successively to a loading station, a displaceable member for controlling the operation of the conveyor moving means, means for moving the displaceable member from an inoperative position to an operative position, and means responsive to the movement of the conveyor for disconnecting the displaceable member from its moving means.

62. In a shoe machine, a conveyor, a plurality of work receiving units carried by the conveyor, means for moving the conveyor to bring the units successively to a loading station, a valve for controlling the movement of the conveyor, a cam carried by the conveyor and arranged in cooperative relation with the valve, and a shiftable member for moving the valve to a position where it initiates the movement of the conveyor, said cam being arranged to move the valve relatively to the shiftable member during the movement of the conveyor.

63. In a shoe machine, a conveyor, a plurality of work receiving units carried by the conveyor, means for moving the conveyor to bring the units successively to a loading station, a valve for controlling the movement of the conveyor, a cam connected with the conveyor and arranged in cooperative relation with the valve, an operator controlled lever for moving the valve to a position where it initiates the operation of the conveyor, and a releasable connection between the operator controlled lever and the valve, said cam being arranged to release said connection during the movement of the conveyor thereby to disconnect the valve from the operator control lever.

64. In a shoe machine, a conveyor, a plurality of work receiving units carried by the conveyor, means for moving the conveyor to bring the units successively to a loading station, a valve for controlling the movement of the conveyor, a cam carried by the conveyor and arranged in cooperative relation with the valve, an operator controlled lever for moving the valve to a position where it initiates movement of the conveyor, a link for connecting the valve with the operator controlled lever, said cam being arranged to impart additional movement to the valve during the progress of the conveyor thereby to disconnect the link from the valve, and a latch for retaining the link in its disconnected position until the operator controlled lever is released.

65. In a shoe machine, a rotatable turret, a plurality of work receiving units carried by the turret, means for rotating the turret to bring the units successively to a loading station, a valve for controlling the movement of the turret rotating

means, a cam carried by the turret and arranged in cooperative relation with the valve, means for urging the valve to an inoperative position, an operator controlled lever for moving the valve to its operative position, a link for connecting the operator controlled lever to the valve, said cam being arranged to impart additional movement to the valve during the movement of the turret thereby to disconnect the link from the operator controlled lever, and a latch for retaining the link in its disconnected position until the lever is released by the operator.

66. In a shoe machine, a turret having a plurality of work receiving units, a fluid motor for rotating the turret successively to bring the units to a loading station, a valve for controlling the operation of the fluid motor, a notched cam connected with the turret and arranged in cooperative relation with the valve, a manually operable lever for opening said valve to initiate the rotation of the turret, and a link for releasably connecting said lever with the valve, said cam being arranged to move the valve relatively to the lever during the rotation of the turret thereby to disconnect the link from the valve so that the latter may seat itself in the next aligning notch and stop the motor regardless of whether or not the manually operable lever has been released.

67. In a machine for operating on shoes, a turret mounted for rotation, a plurality of fluid operated pressure applying units mounted on said turret, a valve for controlling the pressure fluid in certain of the units adjacent to the loading station, a manually operable unit for moving said valve to an inlet position to admit pressure fluid to the unit at the loading station, a control system for moving said valve to an exhaust position, and cams on the turret located in predetermined relation to said units, said cams being arranged to operate the control system, as their associated units move from the station next to the loading station to the loading station thereby to permit the pressure fluid in the unit moving to the loading station to escape.

68. In a machine for applying pressure to a sole and shoe, a pad, gauge mechanism for positioning a sole and shoe on the pad, pressing means for forcing the sole and shoe into the pad, said pressing means including a piston and a piston chamber, and a shiftable member in said piston chamber arranged to effect the withdrawal of the gauge mechanism when the pressure in the chamber reaches a predetermined level.

69. In a machine for applying pressure to a sole and shoe, a pad, gauge mechanism for positioning a sole and shoe on the pad, means for applying pressure to the sole and shoe, a fluid operated shiftable member for controlling the gauge mechanism, a valve for regulating the application of pressure fluid to the shiftable member, manually operable means for moving the valve to one position, and means responsive to the pressure applied to the shoe for moving the valve to another position.

70. In a machine for applying pressure to a sole and shoe, a pad, gauge mechanism for positioning a sole and shoe on the pad, means for applying pressure to the sole and shoe, a fluid operated shiftable member for controlling the gauge mechanism, a valve for regulating the application of pressure fluid to the member, manually operable means for moving the valve to

an inlet position to cause the gauge to position a sole and shoe on the pad, and means responsive to the pressure applied to the sole and shoe to move the valve to an exhaust position when the pressure reaches a predetermined level.

71. In a machine for applying pressure to a sole and shoe, a pad, gauge mechanism for positioning a sole and shoe on the pad, means including a cylinder and a piston for applying pressure to the sole and shoe, a second piston for controlling the gauge mechanism, a valve for controlling the application of pressure fluid to the second piston, manually operable means for moving the valve to one position, and a shiftable member mounted in said cylinder for moving the valve to another position when the pressure in the cylinder reaches a predetermined level.

72. In a machine for applying pressure to a sole and a shoe, a pad, a bail arranged to press a sole and shoe against the pad, gauge mechanism, and means for causing the gauge mechanism to position the sole and shoe on the pad, said means being arranged to urge the bail toward an operative position with respect to the shoe.

73. In a machine for applying pressure to a sole and shoe, a pad, a bail arranged to press a sole and shoe against the pad, gauge mechanism associated with the pad, means including a shiftable member for causing the gauge mechanism to position the sole and shoe on the pad, and connections between the shiftable member and the bail arranged to urge the bail to a position above the shoe.

74. In a machine for applying pressure to a sole and shoe, a pair of bails arranged to press a sole and shoe against the pad, gauge mechanism associated with the pad, means including a shiftable member for causing the gauge mechanism to position a sole and shoe on the pad, and connections between the shiftable member and the bails arranged to urge the bails toward a position above the shoe when the gauge mechanism is operated.

75. In a shoe machine, presser members relatively movable toward and from each other, a piston for pressing one of said members, toward the other, a chamber for said piston, a passageway for conducting pressure fluid to the chamber, said piston being arranged to close the passageway when the pressure level drops, a valve arranged to uncover an escape port opening onto the chamber when the pressure in the chamber is reduced thereby to permit the pressure fluid therein to escape, and a pressure relief valve associated with the chamber and arranged to open and permit the escape of the pressure fluid in the event that the first-mentioned valve fails to uncover the escape port.

76. In a machine for applying pressure to a shoe, a pad, a reciprocating member for pressing a shoe against the pad, a small piston for moving said member rapidly toward the pad, a large piston for exerting heavy pressure on said member, a small piston chamber and a large piston chamber for the small and large pistons respectively, a reversible flow hydraulic circuit for conducting pressure fluid to the small chamber, a passageway for connecting the small chamber with the large chamber, the small piston being constructed and arranged to uncover the connecting passageway in its movement thereby to admit pressure fluid to the large piston chamber, a valve arranged to uncover an escape port opening

onto the large chamber when the pressure in that chamber is reduced thereby to permit the pressure fluid to escape, a passageway connecting the large chamber to the hydraulic system, and a valve in the last mentioned passageway arranged to open when the pressure in the system is reduced and to permit the escape of the pressure fluid from the large chamber in the event that the first-mentioned valve fails to uncover the escape port.

77. In a shoe machine, presser members relatively movable toward and from each other, a small piston for moving one of said presser members rapidly toward the other, a large piston for exerting heavy pressure on one of the presser members, a small piston chamber and a large piston chamber for the small and large pistons respectively, a passageway for connecting the small piston chamber with the large piston chamber, the small piston being constructed and arranged to uncover the connecting passageway in its movement thereby to admit pressure fluid to the large piston chamber, a valve arranged to uncover an escape port opening onto the large chamber when the pressure in that chamber is reduced thereby to permit the pressure fluid in the chamber to escape and the piston to return to its inoperative position, and a pressure relief valve associated with the large piston chamber and arranged to open and permit the escape of pressure fluid from the large chamber in the event that the first-mentioned valve fails to uncover the escape port when the pressure is reduced.

78. In a machine for applying pressure to a shoe, a pad, a reciprocating member for pressing a shoe against the pad, a small piston for moving said member rapidly toward the pad, a large piston for exerting heavy pressure on said member, a small piston chamber and a large piston chamber for the small and large pistons respectively, a passageway for connecting the small piston chamber with the large piston chamber, the small piston being constructed and arranged to uncover the connecting passageway in its movement thereby to admit pressure fluid to the large piston chamber, a spring operated valve arranged to uncover an escape port opening onto the large chamber when the pressure in that chamber is reduced thereby to permit the pressure fluid in the chamber to escape, and a ball valve associated with the large piston chamber and arranged to open when the pressure in the small chamber is reduced thereby to permit the escape of the pressure fluid from the large chamber in the event that the spring operated valve fails to uncover the escape port.

79. In a shoe machine, presser members relatively movable toward and from each other, a small piston for moving one of said presser members rapidly toward the other, a large piston for exerting heavy pressure on one of the presser members, a small piston chamber and a large piston chamber for the small and large pistons respectively, a passageway for connecting the small piston chamber with the large piston chamber, the small piston being constructed and arranged to uncover the connecting passageway in its operating stroke thereby to admit pressure fluid to the large chamber on that stroke and to close that passageway on its return stroke, a spring operated valve arranged to uncover an escape port opening onto the large chamber when the pressure in that chamber is reduced, a second passageway connecting the large chamber with

the small chamber, and a ball valve in the second passageway arranged to permit the escape of pressure fluid from the large chamber in the event that the spring operated valve fails to uncover the escape port.

80. In a machine for applying pressure to a shoe, a pad, a reciprocating member for pressing a shoe against the pad, a piston for operating said member having a small head and a relatively large shoulder spaced from the head, a small piston chamber for the head and a large piston chamber for the shoulder, a passageway for connecting the small piston chamber with the large piston chamber, the head of the piston being constructed and arranged to uncover the connecting passageway in its operating stroke thereby to admit pressure fluid to the large piston chamber, a valve arranged to uncover an escape port opening onto the large chamber when the pressure in that chamber is reduced, a passageway in the piston arranged to connect the large piston chamber with the small piston chamber, and a pressure relief valve in the last mentioned passageway arranged to open and permit the escape of the pressure fluid from the large chamber to the small chamber in the event that the spring operated valve fails to uncover the escape port.

81. In a machine for applying pressure to a sole and shoe, a pad, a reciprocating member for pressing a sole and shoe against the pad, said member being mounted for movement between an inoperative position and a shoe engaging position, means for applying light pressure to the reciprocating member during the initial part of its pressing movement and then a relatively heavy pressure to that member, and a detent associated with the reciprocating member and arranged to prevent its movement to a position where it receives the heavy pressure when the member is in the inoperative position.

82. In a machine for applying pressure to a sole and shoe, a pad, a reciprocating member for pressing a sole and shoe into the pad, said member being arranged for movement between an inoperative position and a shoe engaging position, a piston for operating the reciprocating member, said piston having a relatively small pressure receiving area and a relatively large pressure receiving area which are successively operated upon by pressure fluid, and means connected with the reciprocating member for preventing the application of pressure to the relatively large area of the piston when the reciprocating member is in its inoperative position.

83. In a machine for applying pressure to a sole and shoe, a pad, a bail for pressing a sole and shoe against the pad, said bail being arranged for movement between an inoperative position and a shoe engaging position and for movement through a slot in a relatively fixed plate, a small piston arranged to move the bail rapidly toward the pad, a large piston for exerting heavy pressure on the bail after the sole and shoe have been lightly pressed into the pad, and a member on the bail arranged to engage a side of the slot when the bail is moved by the piston while in its inoperative position thereby to prevent sufficient movement of the piston to permit the application of heavy pressure to the bail.

84. In a machine for applying pressure to a sole and shoe, a pad, a reciprocating member for pressing a sole and shoe against the pad, said reciprocating member being arranged to pass through a slot in the machine frame, a piston

connected with the reciprocating member, and a guide operatively connected with the piston and arranged to prevent rotation in the piston thereby to prevent the reciprocating member binding against the sides of the slot in the frame through which it moves.

85. In a machine for applying pressure to a sole and shoe, a pad, pressure applying means including a member arranged for movement between a shoe pressing position and an inoperative position, a controller for the pressure applying means, and regulating means for the controller effective after pressure has been fully applied to a shoe for insuring the return movement of the member to its inoperative position before the controller can cause said member to press a shoe against the pad a second time.

86. In a machine for applying pressure to a sole and shoe, a pad, pressure applying means arranged for movement between an inoperative position and a shoe pressing position, operating mechanism for said means arranged to operate through a pressing cycle and a release cycle, and regulating means for the operating mechanism effective at the end of the pressing cycle for insuring that the operating mechanism moves completely through its release cycle before the next pressing cycle is initiated.

87. In a machine for applying pressure to a sole and shoe, a pad, means including a piston chamber and a piston for pressing a sole and shoe against the pad, a reversible flow hydraulic circuit connected with the piston chamber, a manually operative valve for regulating the hydraulic circuit, and a regulator for said valve arranged to require the full release of the pressure in the chamber after the maximum pressure has once been applied to the sole and shoe before pressure can be applied a second time.

88. In a machine for applying pressure to a sole and shoe, a pad, means including a piston chamber and a piston for pressing a sole and shoe against a pad, a reversible flow hydraulic circuit connected with the piston chamber, a manually operable valve for regulating the hydraulic circuit, said valve having inlet and exhaust ports, and a regulator for the valve arranged to require the full uncovering of the exhaust port when the valve is first operated after it has been moved to the inlet position.

89. In a machine for applying pressure to a sole and shoe, a pad, means including a piston chamber and a piston for pressing a sole and shoe against the pad, an hydraulic system for conducting pressure fluid to and from the piston chamber, a rotary valve for controlling the hydraulic system, said valve having a passage arranged alternately to be moved to an inlet position and to an exhaust position, a valve collar having a smooth surface approximately corresponding to the length of the movement of the valve from exhaust position to inlet position and a toothed portion approximately corresponding in length to the movement of the valve from the inlet position to exhaust position, and a pawl positioned for engagement with said collar, the smooth surface on the collar being arranged to contact the pawl while the valve is moved from its exhaust position to its inlet position and the toothed section to register with the pawl when the valve reaches its inlet position and to extend through a distance equal to the movement of the valve to its exhaust position.
